FLOWER POT, SAUCER, AND FLOWER-ARRANGING DISC COMBINATION

James E. Bonham, Mount Prospect, and Stanley R. Blackwell, Elmwood Park, Ill., assignors to Quality Molding Company, Addison, Ill., a corporation of Illinois

Filed Mar. 12, 1962, Ser. No. 69,201

Term of patent 3½ years

(Cl. D35—3)

FIG. 1 is a top perspective view of a flower pot, saucer, and flower-arranging disc combination embodying our new design;

FIG. 2 is a bottom perspective view thereof;

FIG. 3 is a side elevational view thereof;

FIG. 4 is a top plan view thereof; and

FIG. 5 is an exploded fragmentary perspective view of the flower-arranging disc and the upper portion of the flower pot of the combination.

We claim:

The ornamental design for a flower pot, saucer, and flower-arranging disc combination, substantially as shown.
